UNITED STATES PATENT OFFICE.

FRANK. E. SAGENDORPH, OF CHICAGO, ILLINOIS, ASSIGNOR OF ONE-HALF TO
E. STARR LLOYD, OF SAME PLACE.

SHEET-METAL ROOFING.

SPECIFICATION forming part of Letters Patent No. 416,348, dated December 3, 1889.

Application filed September 16, 1889. Serial No. 324,114. (No model.)

To all whom it may concern:

Be it known that I, FRANK E. SAGENDORPH, of Chicago, in the county of Cook and State of Illinois, have invented certain new and useful Improvements in Sheet-Metal Roofs, of which the following is a full, clear, and exact description, reference being had to the accompanying drawings, forming a part of this specification, in which—

10 Figure 1 is a plan view of a portion of a roof partially covered with roofing embodying my improvement. Fig. 2 is an enlarged view in detail of a single section of sheet-metal roofing constructed after the manner 15 of my improvement. Fig. 3 is a sectional view taken upon the line $\alpha\alpha$, Fig. 2. Fig. 4 is a side edge view of a portion of said section, and Fig. 5 is a perspective edge view showing the manner of forming the trans- 20 verse joints.

Like letters of reference in the different figures indicate like parts.

The object of my invention is to so crimp or corrugate the respective sections of sheet metal employed in the construction of a roof 25 that when placed together the whole may present the appearance of tile, while at the same time the respective joints may be secure and provision may be made for the expansion and contraction of the metal, all of 30 which is hereinafter more particularly described and claimed.

Referring to the drawings, A, Fig. 1, represents a building, and B the usual roof-supporting frame, to which is attached, by means 35 of nails or other equivalent device, my improved sheet-metal roof-sections C, which consist, respectively, of large sheets, preferably of the usual commercial size, having a 40 series of transverse and longitudinal corrugations d e formed therein. The corrugations d are formed at the respective ends of the sheet or section and at equal distances between and have a bead-shaped appearance, 45 while the corrugations e are wider, the curve thereof representing a longer radius, and they are formed immediately contiguous to each other. In practice I prefer to make the distance between the beads or transverse corrugations d about one-third greater than the width of the corrugations e, which presents the appearance of a series of roofing-tiles connected in the usual way.

In constructing a roof the lower end of each section C overlaps that of the next succeeding section below—that is to say, the bead d upon the given end of a given section covers or overlaps the bead d upon the upper end of the next lower section, as shown at d d', Fig. 5, while one of the corrugations e is made to overlap a corresponding corrugation upon the adjacent section, as indicated in dotted lines in Fig. 3. The respective sections may be secured to the roof by means of nails f, Fig. 1, inserted along the edges and driven into the roof-frame.

A roof, when made in the manner described and properly painted, presents a neat and attractive appearance, and cannot readily be distinguished from a tile roof, while it is much more cheaply constructed and is less liable to leak than a roof of real tile, for the reason that there are fewer joints through which to admit water. Moreover, said corrugations allow for the expansion and contraction of the metal in both directions under varying temperatures without injury to the roof.

Having thus described my invention, I claim—

1. A sheet-metal roof-section having the narrow transverse corrugations d and wider longitudinal corrugations e, substantially as shown and described.

2. The combination, in a sheet-metal roof-section, of the transverse corrugations d and longitudinal contiguous corrugations e, the distance between the former being greater than the width of the latter, substantially as shown and described.

In testimony whereof I have signed this specification in the presence of two subscribing witnesses, this 11th day of September, 1889.

FRANK. E. SAGENDORPH.
